SIDE BEARING

Edwin W. Webb, Chicago, Ill., assignor to Standard Car Truck Company, Chicago, Ill., a corporation of New Jersey

Application June 5, 1933, Serial No. 674,386

3 Claims. (Cl. 308—226)

This invention relates to side roller bearings for cars.

It is the general object of the invention to provide a novel and improved roller side bearing of cheap and simple construction, which can be effectively used and adjusted with ease.

To this end, generally stated, the invention consists in the novel parts and novel combinations of parts, hereinafter defined in the claims and described in the following specification, made in connection with the accompanying drawing, wherein like reference characters refer to the same or similar parts throughout the various views, and, in which:

15 Fig. 1 is a plan view of a side bearing embodying the invention;

Fig. 2 is a vertical section taken on the line 2—2 of Fig. 1 and showing the side bearing applied to the bolster of a car truck; and

20 Fig. 3 is a view looking toward the right end of the side bearing, as shown in Figs. 1 and 2, the bolster of the car truck being shown in vertical section.

A car truck bolster 4 of standard construction is illustrated and this bolster, in accordance with the usual practice, is provided with a number of openings therethrough to permit attachment of side bearings of different designs thereto. One of these openings is designated by the numeral 5.

30 In accordance with the invention there is provided an open topped and open bottomed housing, which may be designated as an entirety by the letter H and which includes side walls 6 and 7, end walls 8 and 9 and feet 10 and 11 joining the lower edges of the side walls and equipped with openings through which rivets or bolts may be passed for securing the housing to the truck bolster 4. The side walls 6 and 7 are preferably provided with openings 12 to lighten the same and at the same time to permit the passage of dust, dirt and the like therethrough.

35 The left end wall 8, as viewed in Figs. 1 and 2 of the drawing, is provided with an opening 13 through its lower portion, which directly overlies the opening in the bottom of the housing. This opening is of less width than the width of the end wall and, accordingly, spaced legs 14 are formed by the lower portions of the wall 8 laterally of the opening 13. Short inturned lugs 15 join the lower ends of the legs 14. Immediately above the opening 13, the end wall 8 is provided with an inturned rib 16 which extends entirely across the wall 8 to overlie the lugs 15 in spaced relation thereabove.

40 The other end wall 9 of the housing is provided

with an opening 17 through its lower portion, which directly overlies the opening in the bottom of the housing. The opening 17 is of the same height as the opening 14 and projects way across between the two side walls 6 and 7. Above the opening 17, the end wall 9 is provided with a cross rib 18 and the end wall above the central portion of the rib 18 is projected outwardly from the remainder of the end wall and provided with an internal recess 19 receiving the head of a bolt 20, the shank of which extends through the end wall and is equipped with a nut 21. Projecting outwardly at the central portion of the top of the end wall 9 is a lip 22. Outwardly disposed from the end of the housing H adjacent the end wall 9 and joining the side walls and cooperating therewith to form guides 23 are wings of angular shape in plan view and these guides have downwardly converging surfaces to receive the correspondingly shaped side edges of a guard G.

45 The guard G is of a width at its lower portion to substantially close the opening 17 in exterior relation thereto and it is equipped at its lower edge with a downwardly projecting wedge-shaped pin 24 adapted to be received within the opening 5 of the truck bolster 4 when the guard G is in lowered position, as shown, and the housing H is properly located and secured on the truck bolster. This guard G has a central, upwardly projecting heavy eye 25, the inner side of which normally bears against the end wall 9. The shank of bolt 20 normally extends through the opening in the eye 25 and the nut 21 is normally drawn up tight against the outer surface of the eye. The upper end of the eye normally immediately underlies the lip 22.

50 The side wall 6 of the housing is preferably provided with an outwardly bulged, inwardly recessed portion 26 set at a comparatively high level and having a downwardly projecting central circularly recessed portion adjoining the same. A small opening is provided in this circularly recessed portion. Directly opposite the opening 27 there is provided in the side wall 7 a larger pin opening 28 through which a roller pin 29 may be inserted to extend across between the side walls 6 and 7 of the housing. This roller pin is somewhat longer than the spacing between the nearest portions of the two side walls 6 and 7 and when raised to its normal position, as shown in Fig. 2, above the openings 27 and 28, one end of the roller pin is received within the recess of the bulged portion 26.

55 The pin 29 projects loosely through an opening in a heavy roller R which fits between the

two side walls of the housing and rests on a tread plate T. This tread plate may be provided with upwardly projecting spaced tread surfaces which diverge sharply from the center of the plate or 5 the plate may be provided with any well known type of tread surface, so as to cause centering action of the roller R on the tread plate. The left end of the tread plate, as viewed in Figs. 1 and 2 of the drawing, is provided with projecting 10 spaced lugs 30 which overlie the lugs 15 and underlie the rib 16 with freedom for considerable vertical movement between the lugs 15 and the rib 16. The other end of the tread plate T is provided with a central outwardly projecting lug 15 15 31 which underlies the rib 18 with freedom for considerable vertical movement relative thereto. To prevent longitudinal movement of the tread plate T to the left, as viewed in Figs. 1 and 2, when it is in position within the housing H, the 20 tread plate is provided at its left end with notches forming shoulders 32 to engage short vertical webs 33 running between the ends of the rib 16 and the lugs 15. Similarly to prevent longitudinal movement of the tread plate to the right, as 25 similarly viewed, the tread plate at its right is provided with shoulders 34 which may engage with lugs 35 extending inwardly from the side walls 6 and 7 respectively and spaced considerably above the lower edges of these side walls. 30 A suitable number of shims S may be disposed within the housing H to rest on the truck bolster 4 and underlie the tread plate T.

In assembling the side bearing, the roller R is first inserted between the two side walls 6 and 35 7 and the pin opening in the roller is aligned with the two openings 27 and 28. The pin 29 is then passed through the pin opening 28 and through the opening in the roller R to be received at one 40 end within the circular recess joining the recess in the bulged portion 26. The roller and pin are then raised upwardly above the level of the two openings 27 and 28. The tread plate T is then inserted in place through the opening in the bottom of the housing H to take its normal position below the roller R with the lugs 30 of the tread plate positioned to overlie the lugs 15 and to underlie the ends of the rib 16. The housing H may 45 then be secured to the truck bolster 4, whereupon the desired number of shims S may be inserted from the right end of the housing, as viewed in 50 Figs. 1 and 2, through the opening 17 to underlie the tread plate T and thereby carry the upper portion of the roller R to the proper level above the housing H for proper use. The bolt 20 if 55 not previously inserted in position, may then be located as shown in the drawing, whereupon the eye 25 of the guard G may be positioned so that the bolt 20 will run therethrough and the lower end of the guard may be dropped into the guides 60 23. The upper end of the guard may then be swung inwardly to the position shown in the drawing, so that it underlies the lip 22. As this is done, the pin 24 of the guard will be received within the opening 5 of the truck bolster 4 and 65 the guard will wedge down in the guides 23. The nut 21 may then be tightened, whereupon the side bearing will be ready for use.

When in use the guard G will, of course, prevent removal of the shims S from the housing. 70 Even if through constant jar on the parts the nut 21 should loosen somewhat, the lip 22 will prevent the guard from raising upwardly to permit removal of the shims. Even if the nut 21 should come way off of the bolt 20, there is very little 75 likelihood that the guard will raise sufficiently

to permit the shims S to slide outwardly through the opening 17 for the reason that the guard G can only be raised by first swinging the upper end of the same outwardly from the end wall 9 and then lifting the same.

It will be seen that if at any time it should be desired to adjust the tread plate T and roller R vertically in the housing H, this can be readily accomplished without removing the side bearing from the truck bolster. The nut 21 can be easily 10 loosened from the bolt 20, whereupon the upper end of the guard G may be swung outwardly beyond the lip 22 from the end wall 9 and then slid upwardly. Additional shims may then be inserted beneath the tread plate T through the 15 opening 17 to raise the height of the roller R or, if desired, one or more shims may be removed from underneath the tread plate to decrease the height of the roller.

It will be seen that an exceedingly simple side 20 bearing has been provided which can be adjusted from time to time by use of shims without difficulty and wherein the shims cannot be removed accidentally.

It will, of course, be understood that various 25 changes may be made in the form, details, arrangement and proportions of the various parts without departing from the scope of the present invention.

What is claimed is:—

1. The combination with a car truck bolster having an aperture therein, of a roller bearing comprising an open topped housing securable to the truck bolster and having a first end wall with an opening therein at its bottom, a roller within said housing, a roller tread plate mounted in said housing below said roller, said roller and tread plate having freedom for common vertical adjustment by shims applicable under said tread plate through the opening in said first end wall and removable from that position, said housing having a second end wall constructed and arranged to prevent removal of said tread plate and any shims applied thereunder through said second end wall, a guard normally fitting over the opening in said first mentioned end wall, said guard having a downwardly projecting pin at its lower edge normally received within the aperture in said truck bolster and anchoring said guard to said truck bolster and means for removably securing said guard to said first mentioned end wall.

2. The combination with a car truck bolster having an aperture therein, of a roller bearing comprising an open topped housing securable to the truck bolster and having a first end wall with an opening therein at its bottom, a roller within said housing, a roller tread plate mounted in said housing below said roller, said roller and tread plate having freedom for common vertical adjustment by shims applicable under said tread plate through the opening in said first end wall and removable from that position, said housing having a second end wall constructed and arranged to prevent removal of said tread plate and any shims applied thereunder through said second end wall, a guard normally fitting over the opening in said first mentioned end wall, said guard having a downwardly projecting pin at its lower edge normally received within the aperture in said truck bolster, means for removably securing said guard to said first mentioned end wall, and means preventing said guard from being removed by raising the same until the upper end 75

of said guard has been swung for some distance away from said first end wall.

3. The combination with a car truck bolster having an aperture therein, of a roller bearing comprising an open topped housing securable to the truck bolster and having a first end wall with an opening therein at its bottom, a roller within said housing, a roller tread plate mounted in said housing below said roller, said roller and tread plate having freedom for common vertical adjustment by shims applicable under said tread plate through the opening in said first end wall 10 and removable from that position, said housing

having a second end wall constructed and arranged to prevent removal of said tread plate and any shims applied thereunder through said second end wall, a guard normally fitting over the opening in said first mentioned end wall, said guard having a downwardly projecting pin at its lower edge normally received within the aperture in said truck bolster, and means preventing said guard from being removed by raising the same until the upper end of said guard has been swung 10 for some distance away from said first end wall. 5
